UNITED STATES PATENT OFFICE.

GARFIELD R. WATKINS AND HENRY WUERTZ, OF CINCINNATI, OHIO.

WASHING-MACHINE.

1,181,812.

Specification of Letters Patent.

Patented May 2, 1916.

Application filed May 28, 1914. Serial No. 341,520.

To all whom it may concern:

Be it known that we, GARFIELD R. WATKINS and HENRY WUERTZ, citizens of the United States, residing at Cincinnati, in the county of Hamilton and State of Ohio, have invented certain new and useful Improvements in Washing-Machines, of which the following is a specification.

This invention relates to power operated washing machines, and has for its object to provide a device of this character embodying a traveling endless conveyer carrying scrubbing strips and a roller disposed over the conveyer having circumferential corrugations and reciprocable transversely of the endless conveyer.

Another object is the provision of simple and efficient driving means for the conveyer and roller.

Another object is the provision of a machine of this character embodying a pivoted roller support adapted to automatically adjust itself to the quantity of material passing thereunder.

With these and other objects in view, the invention consists in the novel construction, arrangement and formation of parts as will be hereinafter specifically described, claimed and illustrated in the accompanying drawings, in which,

Figure 1 represents a top plan view of the washing machine, and, Fig. 2 represents a side elevation thereof, Fig. 3 represents a longitudinal sectional view taken on the line 3—3 of Fig. 1, Fig. 4 represents a transverse sectional view taken on the line 4—4 of Fig. 1 looking in the direction of the arrow, Fig. 5 represents a detail view showing one of the links of the chain.

Referring to the drawing in detail, where-in similar reference numerals designate corresponding parts throughout the several views, the numeral 5 indicates a suitable container formed of sheet metal or other suitable material suitably supported upon legs 6 and braces 7 preferably formed of angle irons. The bottom wall of the container 5 is inclined downwardly and inwardly from the opposite end walls thereof, as illustrated in Fig. 2. Shafts 8 and 9 are rotatably mounted on the side walls of the liquid container adjacent the opposite ends thereof, and each shaft carries a pair of sprocket wheels 10 secured thereon a distance inwardly of the adjacent side wall of the container. A third shaft 11 is mounted

through the side wall of the container adjacent the center thereof a distance below the shafts 8 and 9 and also carries a pair of sprocket wheels. Chains 12 are adapted to travel on the sprocket wheels 10 of the shafts 8, 9 and sprocket wheels 10^a of the shaft 11. Between the upper and lower portions of the chains 12 idler shafts 13 are rotatably mounted in the side walls of the liquid container 5 and carry suitable pulleys 14 on which the chains travel. The chains 12 are composed of a plurality of links, which have a body portion 12^a, a flange 12^b extending along one side edge thereof and provided with an opening 12^c for securing the slats or strips 15 thereto, a loop 12^d is formed on one end of the body portion, and a hook 12^e is formed on the opposite end for securing the links together. A plurality of slats or strips 15 have their ends secured to the flanges 12^b of the links of the chains, and constitute in connection with said chains an endless conveyer.

One end of the shaft 9 carries a pulley 16 preferably formed with a groove to receive the belt or the like 17 traveling on a second pulley 18 carried by a bevel gear wheel 19. The bevel gear wheel 19 and pulley 18 carried thereby are non-rotatably mounted on one end of the shaft 8. Shaft supports 20 are secured to one of a pair of arms 27 and rotatably support a shaft 21 carrying at one end a pulley 22 provided with a suitable crank handle 23 and carrying at its opposite end a disk 24 provided with an eccentric pin 25. Intermediate the supports 20 the shaft 21 is provided with a bevel gear wheel 26 meshing with the teeth of the gear wheel 19 and adapted to drive the latter.

The outer ends of a pair of arms 27 are pivotally supported on the shaft 8 and the opposite ends of said arms are provided with bearings 28 rotatably receiving a central shaft 29 disposed above the side walls of the liquid container 5. The inner extremities of the arms 27 are provided with depending headed rods 30 slidably mounted in suitable bearing members 31 secured to the outer faces of the side walls and adapted to guide the movement of the arms 27. A cylinder 32 is rotatably mounted on the shaft 29 between the bearings 28 and is provided with a plurality of circumferential corrugations. The cylinder 32 projects a distance into the liquid container 5 and nor-

normally rests upon the top portion of the strips 15.

A pair of wringer rollers 33 are rotatably mounted in suitable standards 34 secured to the end of the liquid container 5 in which the shaft 9 is mounted. The upper roller 33 is adjustably supported by suitable screws 35 and the lower roller is provided on one end with a gear wheel 36 meshing with a gear wheel 37 carried on the end of the shaft 9 opposite from the pulley 16. The wringer rollers 33 are constantly driven during the operation of the washing machine through the pinions 37 and 36. The end of the shaft 15 29 adjacent the shaft 21 is provided with a yoke 39 having a vertically disposed opening therein receiving the eccentric pin 25.

In operation, the pulley 22 is connected with a suitable source of power to drive the shaft 21 and the bevel gear wheel 26 and disk 24 carried thereby. The pin 25 carried by the disk 24 works within the vertical opening of the yoke 39 reciprocating the shaft 29 and cylinder 32 transversely within the liquid container 5. The driving shaft 9 for the endless conveyer is driven from the shaft 21 through the pinions 26, 19, pulley 18, belt 17 and pulley 16. The rollers 33 are driven from the shaft 9 through the pinions 37 and 36. The articles to be washed are introduced into the container at one end between the cylinder 32 and the shaft 8, the top portion of the endless conveyer carrying the strips 15 travels toward the opposite end of the liquid container 5 and carries the articles underneath the cylinder 32 which latter effectively scrubs the articles by its reciprocation thereover.

40. It will be understood that the cylinder 32 is normally retained against the articles being washed by its own weight and as the

articles are moved from under the cylinder they are deposited by the conveyer between the rollers 33 of the wringer and drawn 45 between the rollers by the rotation thereof.

What we claim is:—

1. A washing machine comprising a container, an endless conveyer operable in said container, a pair of arms pivotally mounted in said container, a shaft rotatably mounted longitudinally of one of said arms, a second shaft rotatably mounted in the free ends of said arms and having one end enlarged and provided with a vertical opening, an 55 eccentric pin carried by the first shaft engag- gaging within said vertical opening, and a cylinder rotatably mounted on the second mentioned shaft.

2. A washing machine comprising a con- tainer, an endless conveyer operable in said container, a pair of arms pivotally secured at their outer extremities to said container, a horizontally disposed shaft, bearing mem- bers carried by one of said pivoted arms 65 rotatably supporting said shaft, a second shaft rotatably mounted in the inner ex- tremities of said arms, a cylinder rotatably mounted on the second-mentioned shaft, a yoke secured to the second-mentioned shaft 70 having a vertical opening therein, an ec- centric pin carried by the first-mentioned shaft operably engaged within said verti- cal opening, guide rods secured to the free ends of said arms, and apertured members 75 secured to said container slidably receiving said guide rods.

In testimony whereof we affix our signatures in presence of two witnesses.

GARFIELD R. WATKINS.
HENRY WUERTZ.
